UNITED STATES PATENT OFFICE.

ERNEST R. HAMMER, OF ST. LOUIS, MISSOURI.

TOILET-SEAT PAPER AND HOLDER.

1,168,801.

Specification of Letters Patent.

Patented Jan. 18, 1916.

Application filed April 19, 1915. Serial No. 22,414.

To all whom it may concern:

Be it known that I, ERNEST R. HAMMER, a citizen of the United States, and resident of St. Louis, State of Missouri, have invented certain new and useful Improvements in Toilet-Seat Paper and Holders, of which the following is a specification containing a full, clear, and exact description, reference being had to the accompanying drawings, forming a part hereof.

The objects of my invention are to construct a holder for properly shaped sheets of toilet tissue in such position with respect to the seat that the paper can be removed from the back and on to the seat, the connection between the back and paper being such as to hold the paper in proper position, the paper and back being so constructed that the paper is always held firmly together rigidly away from the seat and that but few sheets can be removed at a time, and that the device cannot be unlocked for refilling until the last sheet of paper has been used.

With the above and other objects in view, my invention has relation to certain novel features of construction and operation, examples of which are described in the following specification and illustrated in the accompanying drawings in which—

Figure 1 is a side elevation of a conventional toilet seat with my device attached. Fig. 2 is a plan view of a toilet seat with my device attached. Fig. 3 is a front elevation of a detail of a toilet seat with my device attached. Fig. 4 is a sectional elevation along the line 4—4 of Fig. 3. Fig. 5 is an enlarged detail sectional elevation of the upper portion of my device. Fig. 6 is an enlarged detail plan of the upper portion of my device. Fig. 7 is a detail plan of a spring used in my device shown in Fig. 4 and Fig. 8 is a detail plan of a member of my device shown in Fig. 4.

In the drawings numeral 9 designates a conventional toilet seat on which at its rear portion is screwed the hinge member 10; 11 is a hinge member which is secured to the back 12 of the seat 9 by the screws 13.

14 is a rod bent into an L shape pivotally secured to the pintle 15 at its one extremity and extending through a hole 16 in the toilet tissue 17 with its other extremity. Hinge members 10 and 11 are pivotally secured to the pintle 15 at their free ends.

18 designates a depression in the seat

back 12, gouged out in the ordinary manner; 19 represents a flat spring secured to back 12 by the screw 20. Spring 19 is of such a length as to be adjacent the free end 60 of bent rod 14 when in the position shown in Fig. 4.

21 represents a flat plate secured to back 12 by screws 22 and of such a length as to be adjacent the free end of bent rod 14 65 when in the position shown in Fig. 4. Spring 19 and plate 21 have their free ends cut as shown at 23 and 24 on Figs. 7 and 8 so as to clear bent rod 14 when in the position shown in Fig. 4.

To fill my device with toilet tissue, bent rod 14 is rotated in the direction indicated by the arrow on Fig. 4 about the pintle 15. It will be discerned that such rotation is precluded by the end of angle iron 25 coming in contact with the end 26 of spring 19. To rotate the bent rod iron 14 as indicated by the arrow on Fig. 4, it will therefore be necessary to compress spring 19 into depression 18 thereby allowing sufficient clearance 70 for point 25 to pass. Bent rod 14 can then be brought into the position as indicated by the dotted lines. The paper may now be placed in position with its bottom edges resting on the hinge member 11 and bent 75 rod 14 is then rotated back through the openings 16 in the toilet tissue, compressing spring 19 into the depression 18 until point 25 is released whereupon the paper and bent rod 14 will assume the position shown in 80 Fig. 4. Plate 21 serves to prevent bent rod 14 from rotating too far in the opposite direction of the arrow as indicated in Fig. 4.

The upper ends of the tissue are secured by the device shown in Figs. 5 and 6. 27 95 designates a hook elliptical in section at its extremity 28 and terminating in a dull knife edge at 29; the shank 30 is rectangular in section and passes through the rectangular opening 31. The end 32 of hook 27 is 100 threaded to fit the internal threads 33 of cap 34. 35 represents a cup shaped casting having the flanges 36 which are secured to the back 12 by means of the screws 37. Cap 34 and the end 32 of the hook 27 are slidably secured in the cup 35 as shown in Fig. 5. 38 designates a coil spring wound around a portion of the end 32 and between the hook and the cap 34. The spring 38 is not in compression when knife edge 29 rests 110 against back 12, i. e., to say when the holder is empty. As the hook 27 is pulled out

spring 38 is compressed; therefore knife edge 29 is continually kept in absolute contact with the outer sheet of tissue paper. The removal of tissue causes the spring 38 to expand and to move the hook and cap 34 inwardly. By this means, the upper ends of the tissue are held in position.

The operation of my device is as follows:—

To remove a sheet of paper from the holders 10 to the seat, grasp the outer sheet 39 and pull in the direction of the arrows in both Figs. 4 and 5; this will pull the sheet over the hook tearing a small hole at the knife edge 29. By pulling farther over the bent rod 14 the 15 paper will cover the hinge member 10 and the hole in the paper will register with the hole in the seat. After use, the paper may be torn along the edge 40. By this means a simple, compact and rigid device for holding the paper in spaced relationship with the seat is obtained.

What I claim is—

1. In a device of the character described 25 toilet tissue, a hook, having a shank threaded at its extremity, a cup shaped casting, a coil spring, and a threaded cap, said coil 30 spring being placed around the shank of said hook and adjacent the inner surface of said cup shaped casting, said cap screwing on the threaded extremity of the shank of 35 said hook, said toilet tissue positioned between said hook and said cup shaped casting, said spring being normally in compression, thereby holding the point of said hook in close contact with said toilet tissue.

2. In a device of the character described, a toilet seat, a seat back, toilet tissue, a pintle, a flat spring firmly secured to said seat back, at one extremity between said tissue and said back, the other extremity of said 40 spring free to vibrate in an aperture in said seat back, hinge members, one of which is firmly secured to said seat back at its one extremity another of said hinge members being firmly secured to said seat at its one 45 extremity, the other extremities of said hinge members revolubly secured to said pintle, a bent rod revolubly secured to said pintle at one end its other extremity extending through apertures in said toilet tissue. 50

3. In a device of the character described, a seat back, toilet tissue, a cup shaped casting firmly secured to said seat back, a hook having a knife edge point extending through a hole in said tissue, a coil spring 55 and a cap, said spring encircling the shank of said hook and slidably positioned in said cup, said cap slidably secured in said cup, and firmly secured to the shank end of said hook, said spring being normally in compression 60 so as to hold the knife edge point of said hook in contact with said toilet tissue.

In testimony whereof, I have signed my name to this specification, in the presence 65 of two subscribing witnesses.

ERNEST R. HAMMER.
